UNITED STATES PATENT OFFICE.

SAMUEL DAVID LINDSAY, OF ORLANDO, FLORIDA.

CONCRETE-BLOCK MACHINE.

1,241,228.

Specification of Letters Patent. Patented Sept. 25, 1917.

Application filed January 18, 1915. Serial No. 2,867.

To all whom it may concern:

Be it known that I, SAMUEL DAVID LINDSAY, a citizen of the United States, residing at Orlando, in the county of Orange and State of Florida, have invented certain new and useful Improvements in Concrete-Block Machines, of which the following is a specification.

The invention relates to concrete block machines and has for its object the provision of a simple and efficient machine of the character mentioned which is adapted for use in forming blocks or bricks of concrete, or other plastic material, in different sizes.

Other objects will appear hereinafter.

My improvement consists substantially in the combination and arrangement of parts hereinafter described and claimed, and will be best understood by referring to the accompanying drawings, forming a part of this specification and in which—

Figure 1 is a plan view of a block forming machine embodying my invention;

Fig. 2 is an end elevation of the same;

Fig. 3 is a perspective view of a finished block;

Fig. 4 is an enlarged fragmental section taken on line 4—4 in Fig. 2;

Fig. 5 is an enlarged fragmental section taken on line 5—5 in Fig. 1;

Fig. 6 is a view similar to Fig. 5 but showing some of the parts of the machine in different positions than shown in said Fig. 5;

Fig. 7 is an enlarged fragmental section taken on line 7—7 in Fig. 1;

Fig. 8 is a perspective view of a pallet used to form one side of the mold of the machine in forming a block; and

Fig. 9 is a section taken on line 9—9 in Fig. 7.

The device consists, generally, in a supporting frame upon which is mounted a suitable molding form and operating mechanism adapted to move certain portions of the form into and out of operative condition. The frame is so constructed that molds of different sizes may be supported and operated thereon.

Referring more particularly to the drawing, the frame comprises four corner posts 9 connected by members 10 which extend

transversely of the machine and form end members therefor. The end members 10 are spaced apart by means of bars 12, 13 and 14, the latter being secured to said end members 10 by means of bolts or their equivalent. Two of the posts 9 on one side of the machine, preferably the rear side thereof, are provided with upstanding extensions 11 which are smaller in cross section than the lower portions of the posts. Rigidly mounted in the bars or members 10 and extending longitudinally of the machine are two parallel bars 15 forming guides upon which the end members of the molding form are slidably mounted. The mountings for the end members of the molding form comprise angle bars 16 having suitable horizontal perforations engaging the guides 15 and permitting such angle bars to be moved toward and away from each other upon the guides. Secured to each of the angle bars 16 and rising perpendicularly therefrom are two uprights 17, one of said uprights being rigidly secured to one of the angle bars 16 and the other of the uprights 17 being removably secured to one of the angle bars 16, the arrangement being such that the last mentioned upright 17 may be secured to its corresponding angle bar 16 at perforations 19 by bolts 19' or their equivalent. The purpose of securing the movable uprights 17 in different positions on the angle bars 16 is to provide means for holding end portions of the molds of different sizes. Thus it will be seen that in holding the smallest size of the end portions of the molds the movably secured uprights 17 will be secured in their positions indicated in Fig. 4, and when it is desired to use end portions of the mold for molding larger blocks such movable uprights 17 are moved to the different perforations 19 and secured to the angle bars 16 corresponding to the size of end portion it is desired to use, as will be readily understood. The end portions 18 of the mold are secured to the uprights 17 in any approved manner, the connection indicated being screws 17' passing through the uprights 17 into the end portions (Fig. 7).

Pivoted to the central portion of bar 12, as at 20, is a lever 21. Near one end of the

lever 21 is a perforation adapted to register with perforations 23 formed in bar 14. A pin 22 is adapted to pass through the perforation in lever 21 and one of the perforations 23 to lock the lever 21 against pivotal movement and in different positions of its pivotal movement. The angle bars 16 are connected to the lever 21 by means of connecting rods or bars 24 and 25 in a manner that upon swinging the lever 21 upon its pivotal point the angle bars 16 will be moved on guides 15 toward and away from each other. The bars 24 and 25 have their adjacent ends perforated and connected, as at 26, by means of a pin and slot connection with lever 21. The other ends of said bars 24 and 25 are rigidly secured to the angle bars 16. From this arrangement it will be seen that the angular arrangement of the bars 24 and 25 will maintain the angle bars 16 in parallel relation to each other at all of their positions on guides 15. To facilitate maintaining the uprights 17 in parallel positions supporting members 27 are secured to the bars 24 and 25 and slidably mounted on the guides 15. These supports 27 operating with the guides 15 also maintain the bars 24 and 25 in substantially the same plane thereby preventing pivotal movement of the angle bars 16 on the guides 15. The pivotal movement of lever 21 is of a sufficient length to permit the different or desired sizes of molding forms to be used in forming blocks of different sizes and also to move the end portions 18 of the form away from the finished block after the latter has been molded.

One side of the molding form 28 is secured to the uprights 11 and is provided with perforations 29 through which core molds 30 are adapted to pass to enter the molding forms. The core molds 30 are secured to angle bars 31 which extend laterally of the core molds and are provided with perforations engaging guides 32. The arrangement is such that when the core molds 30 are moved out of the molding form, as shown in Fig. 6, their ends will still be in openings 29. This arrangement provides means for preventing the loss of material while the lower portion of the form is being filled. Guides 32 are supported by having their forward ends secured to bar 34 carried by uprights 11 and their central portions secured to pins or projections 33 on the upturned end portions 33 of the bar 13, see particularly Figs. 5 and 6. Secured across the outer portions of the guides 32 is a cross bar 35 which carries a bumper 36, the latter being of a yielding material such as rubber. The cross bar 35 is positioned to limit the outer movement of the core molds 30 and prevent the inner ends of such molds from being removed from the openings 29.

The form or mold members are placed in

their positions indicated in Fig. 5 to begin 65 the molding operation, except the core molds 30 which are placed in their positions indicated in Fig. 6. Concrete or other plastic material is then tamped in the mold until it reaches the bottoms of openings 29 in side 70 28 when the core molds are moved into the mold to their positions indicated in Fig. 5 and more plastic material added to fill the mold. I form the core molds 30 hollow with their front ends open and openings 30' near 75 their rear ends so that if some of the plastic material extends into the path of the core molds the latter will cut through such material and remove it from the path. Where core molds are formed solid any material 80 in their paths would likely be pressed against the pallet 45 and require extra labor to smooth the finished block.

The core molds 30 are moved on their guides by means of lever 37 which is pivoted, as at 38, to cross bar 13. The upper end of lever 37 engages a suitable perforation in one of the angle bars 31, as indicated in Figs. 5 and 6. The lower end of lever 37 is connected by means of a connecting link 39 to a manually operable lever 40, the latter being pivoted at a point 41 to a bar 42 and such bar secured to two of the posts 9. The lever 40 has its handle end disposed in a convenient position to the operator near the handle end of lever 21 so that one operator may operate the machine without changing his position. It will be seen that upon throwing the upper end of lever 40 toward the front of the machine, or the side at 100 which the lever 21 has its handle end, the core molds 30 will be moved into the mold form to positions, such as indicated in Figs. 2 and 5. Upon throwing the upper end of lever 40 in an opposite direction the core 115 molds will be moved out of the molding form to positions such as indicated in Fig. 6.

On the front side of the machine and disposed between end members 10 are a plurality of parallel bars or rods 43, each of 110 which is adapted to form the pivotal point for angle members 46. A bottom 44 is secured to one set of the parallel portions of the angle members 46 and adapted to have its end portions rest on the upper edges of 115 the end members 10 when in operative condition. When it is desired to mold a block of the smallest size for which the machine is designed the angle members 46 are pivoted on the innermost of the round bars 43, as 120 indicated in Figs. 5 and 6, and when a block of larger size is desired, bottom 44 is removed and a bottom of the desired size secured to the angle members 46 and the pivotal point of such members is moved to another of the bars 43 toward the front of the machine, the bar 43 being selected which 125 will permit one edge of the new bottom 44

to engage the lower edge of back 28, as will be readily understood.

The other set of parallel portions of angle members 46 are provided with guides 47 and 5 such guides are adapted to be engaged by tongues 48 formed on cleats 49 of a pallet 45 in order to removably hold such pallet 45 in position to form one side of the molding form. From this arrangement then it will 10 be seen that to adjust the pallet 45 to angle members 46 or to remove it therefrom it is only necessary to slide the pallet 45 on to and from the second mentioned set of parallel arms of members 46. In forming the blocks a separate pallet 45 is used for each block. After the pallet is used in forming the block such block is permitted to rest on the pallet until thoroughly dried before removing therefrom. By using the pallet for one side of 20 the form in molding the blocks there is little or no danger of breaking the block while still wet in transferring it to the place where it is to be dried.

A hoop or ring 50 is pivoted, as at 51, to 25 the upper end portions of uprights 11 and adapted to engage the upper ends of uprights 17 and the upper ends of the set of arms of the angle members 46 which support the pallet 45 in order to lock the ends 18 bottom 44 and side 45 in operative condition during 30 the process of forming a block in the machine. At the upper ends of the set of arms of angle members 46 which support the side 45, are provided rings 53 which form handles 35 holds to facilitate moving the angle members 46 on their pivotal points, and formed on the rings 53 are stops 54 serving to support one side of ring 50 and maintain said ring in operative condition. The ring 50 is 40 preferably made of sections secured together by means of bolts 52 or their equivalent. Adjacent the ends of the portions making up ring 50 are provided a plurality of 45 perforations so that such portions may be adjusted to form rings of larger or smaller sizes to accommodate molding forms of different sizes, as will be readily understood.

From the construction shown it will be 50 observed that portions of molding forms for molding one size of block may be easily secured in the machine, and when desired, portions of a molding form of a different size may be secured in the machine in place of the first mentioned molding forms, also that 55 the parts are so arranged that only one operator is required to operate the machine. It is also obvious that the inner surface of the molding forms may be shaped in any suitable configurations in order to produce 60 any desired faces on the finished blocks.

While I have described and illustrated the preferred form of construction of my invention I do not desire to be limited to the precise form shown and described but desire

to avail myself of such variations and 65 changes as may come within the appended claims.

1. A concrete block machine comprising a support; parallel guides in said support; a form having end walls slidably mounted 70 on said guides; a lever pivoted in said support between said end walls; two converging members, having their diverging ends secured to one of the end walls and their converging ends disposed adjacent one of said guides; slot and pin connections between the converging ends of said members with said lever; and supports secured to certain of said members adjacent said slot and pin connections and slidably mounted on one of the 80 guides.

2. A concrete block machine comprising a support; two parallel guides in the support; a block molding form having end walls; supporting members carrying said end walls and 85 each of said supporting members having two points of support slidably mounted on one of the guides and one point of support slidably mounted on the other of said guides, 90 said supporting members being adapted to maintain the end walls in substantially parallel relation in all of their positions on said guides; and a lever pivoted in the frame between said end walls and connected to said supporting members for moving the latter 95 simultaneously on said guides.

3. A concrete block machine comprising a support; parallel guide bars in the support; two parallel members disposed transversely of and slidably mounted on said guide bars; a molding form on the support, the sides and bottom of the form being mounted on the support and the ends of said form being mounted on said parallel members; a lever pivoted in the support between the parallel members; connecting bars having one end of each secured to one of the parallel members and the other end of each connected by means of a pin and slot connection with the lever; and members secured on certain of the connecting bars adjacent the lever and slidably mounted on the guide bars.

4. A concrete block machine comprising a support; parallel guide bars in the support; two parallel members disposed transversely of and slidably mounted on said guide bars; a molding form on the support, the sides and bottom of the form being mounted on the support and the ends of the form being mounted on said parallel members; a lever pivoted in the support between the parallel members; pairs of connecting bars, each pair comprising two bars disposed at an angle to each other with their diverging ends secured to one of said parallel members and their converging ends connected with said lever; members, each secured to one of said connecting bars near the connection of the latter 125

with said lever and slidably mounted on one of the guide bars, said last mentioned members and said parallel members providing three-point supports for the end walls maintaining said end walls parallel in all of their positions on said guide bars.

In testimony whereof I have signed my

name to this specification, in the presence of two subscribing witnesses, on this 11th day of January, A. D. 1915.

SAMUEL DAVID LINDSAY.
